FIG. 1 is a front elevation view of sauna waist trainer sweatpants, showing my new design;
FIG. 2 is a left side elevation view thereof of which the right side elevation view is symmetrical;
FIG. 3 is a rear elevation view thereof;
FIG. 4 is a top plan view thereof;
FIG. 5 is a bottom plan view thereof;
FIG. 6 is a front close-up view of a top portion thereof in an open configuration;
FIG. 7 is a front close-up view of a top portion thereof in a partially open configuration; and,
FIG. 8 is a front close-up view of a top portion thereof in a closed configuration.

The small evenly spaced broken lines shown in the drawings depict stitching that forms no part of the claimed invention.

The dot-dash broken lines in the drawings represent the boundaries of the claim and form no part of the claimed design.
